UNITED STATES PATENT OFFICE.

THEODORE WEILER, OF MEDICAL LAKE, WASHINGTON.

TIE PLATE.

Application filed June 23, 1924. Serial No. 721,671.

To all whom it may concern:

Be it known that I, THEODORE WEILER, a citizen of the United States, residing at Medical Lake, in Spokane County, and State of Washington, have invented certain new and useful Improvements in Tie Plates, of which the following is a specification.

My present invention relates to improvements in tie plates for use in railway construction and designed as a practical comparatively inexpensive and efficient means for securing the railway rail to its ties. As is well known in track laying and railway operations it is imperative that creeping, lateral movement, and tipping or tilting of the rails shall be prevented, and that the tie plate itself be rigidly fastened to the tie. For compliance with these requirements my tie plate has been especially constructed.

The invention consists in certain combinations and arrangements of features of construction in a single, integral, tie plate, as will be hereinafter more fully set forth and claimed.

In the accompanying drawings I have illustrated one complete example of the physical embodiment of my invention wherein the parts are combined and arranged according to the best mode I have thus far devised for the practical application of the principles of my invention.

Figure 1 is a view showing a standard railroad rail in cross section, and a tie plate constructed according to my invention securing the rail in place on a portion of a cross tie.

Figure 2 is a perspective view of the tie plate showing in dotted lines the relation thereto of the rail.

Figure 3 is a bottom plan view of the tie plate.

For purposes of illustration I have indicated in Figure 1 a portion of a tie T and a standard railway rail with its head H, web W and base B, the latter having the longitudinal flanges B' and B² as usual.

The tie plate 1 is of rectangular shape having on its bottom intersecting ribs 2 which extend longitudinally across the plate in two series, the parallel ribs of one series intersecting the parallel ribs of another series. These ribs are designed to be embedded in the top surface of the wood tie T, and because of their arrangement and disposition on the bottom of the plate, the

ribs prevent horizontal movement of the plate in any direction.

On its upper face the tie plate near one side is fashioned with a longitudinally disposed lug 3 having an inner abutment or shoulder 4 perpendicular to the top face of the tie plate, against which shoulder the edge of the flange B² of the rail abuts when the tie plate and rail are properly positioned.

A plurality of spike holes 5 are provided for the spikes, as S, which holes extend through the lug 3 and the plate for the accommodation of the spikes, in order that the lip S' of the spike as seen in Figure 1 will project over the edge of the flange B² of the rail base. By this arrangement of parts the edge of the rail base is retained in close engagement with the shoulder 4 and the lip of the spike holds the edge of the flange down on the tie plate.

Near the opposite side of the tie plate on its upper surface is fashioned an integral, overhanging flange 6 which extends inwardly toward the longitudinal center of the plate and is provided with an undercut space 7 at its junction with the body of the plate. On its under side the overhanging flange is fashioned with a contact face 8 for frictional engagement with the top inclined surface of the flange B' of the rail. The flange is undercut in order that the space 7 may afford clearance for the rail-flange, and to insure a resilient or spring-like frictional pressure of the flange 8 on the rail-flange without subjecting the flange 6 to strains that would otherwise tend to break off the flange at its junction with the tie plate. The surface 8 is also inclined to conform to the inclination of the top surface of the rail flange to insure a wedge and close frictional engagement of these parts.

A single spike hole 9 extends through the tie plate at the outer side of the flange 6 for the reception of a spike that is driven therethrough and into the railway tie.

In assembling the plate and rail, the body of the plate is slipped under the rail base with the flange 6 extending over and embracing the flange B' of the rail base. Then the plate is driven or forced in direction transversely of the rail in order that a wedge action may be secured between the plate and its flange over the flange of the rail

base. The flange B' of the rail is thus held in frictional engagement between the upper face of the plate and the inclined face 8 of the plate-flange to insure a rigid interlocking of these parts. In this position the outer edge of the flange B² of the rail base abuts against the shoulder 4 in close frictional contact therewith. The rail and plate are now lowered to the tie and the spikes S are driven through the spike holes to secure the plate and rail to the tie.

The tie plates are spaced at the required intervals along the rail where necessary, and as the plates are interchangeable, the flange 6 of the plate may be located at either the inside or the outside of the rail. In some instances the plates may be arranged with the flanges 6 in alternate positions at the inside and outside of the rail. When the plates are in use it will be apparent that

the rail is held in position against lateral displacement in either direction and against tilting movement, as well as against excessive creeping movement.

Having thus fully described my invention, what I claim and desire to secure by Letters Patent is—

A tie plate having on its bottom two series of diagonally extending, intersecting ribs, a longitudinally extending integral lug on its upper face and an inner shoulder on said lug perpendicular to the top surface of the tie plate, and a spaced overhanging parallel flange with an undercut clearance at its junction with the top surface of the plate and fashioned with an inclined frictional contact face on its under side.

In testimony whereof I affix my signature.

THEODORE WEILER.
